UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET HANDLE.

● **40,465.**

Specification for Design.

Patented Jan. 25, 1910.

Application filed November 8, 1909. Serial No. 526,937. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawings, forming a part thereof.

The figure is a front elevation of a burial-casket handle, showing my new design, one end of the handle-bar being broken away.

I claim:

The ornamental design for a burial-casket handle, as shown.

CHARLES BLESCH.
